(57) CLAIM

I claim the ornamental design for a hand held sweeper, as shown and described.

DESCRIPTION

FIG. 1 is a perspective view taken from the right top front corner of the hand held sweeper showing the new design; FIG. 2 is a perspective view taken from the left top rear corner of the hand held sweeper; FIG. 3 is a front view thereof; FIG. 4 is a rear view thereof; FIG. 5 is a left side view thereof; FIG. 6 is a right side view thereof; FIG. 7 is a top plan view thereof; FIG. 8 is a bottom view thereof; and, FIG. 9 is a perspective view taken from the left bottom rear corner of the hand held sweeper. The broken lines in the drawings depict environmental subject matter only and form no part of the claimed design.
